UNITED STATES PATENT OFFICE.

EDWARD A. KAUMEYER AND DAVID M. BLOOM, OF CHICAGO, ILLINOIS; SAID KAUMEYER
ASSIGNOR TO SAID BLOOM.

SEWING-MACHINE.

1,300,843.

Specification of Letters Patent. Patented Apr. 15, 1919.

Application filed January 2, 1918. Serial No. 209,863.

To all whom it may concern:

Be it known that we, EDWARD A. KAUMEYER and DAVID M. BLOOM, citizens of the United States, and residents of Chicago, 5 Cook county, and State of Illinois, have invented certain new and useful Improvements in Sewing-Machines, of which the following is declared to be a full, clear, and exact description.

10 This invention relates to sewing machines and its primary object is to provide a sewing machine for sewing the lower ends of sleeve lining to the coat sleeves. Heretofore, this operation has been done by hand because of the absence of any machine capable 15 of satisfactorily performing this particular sewing operation. Another object of this invention is to provide a sewing machine by means of which the stitches in the completed article are caused to resemble hand sewed stitches. Another object is to provide a machine by which the operation of sewing the lower end of the sleeve lining to the coat sleeve may be accomplished 20 quickly and with much greater ease than the laborious task of performing this operation by hand. Another object is to provide a machine which will produce even, finished stitches in sewing the sleeve lining 25 to the coat sleeve. Other objects and advantages will appear in the following specification, and with all of said objects and advantages in view, this invention consists in the several novel features of construction, 30 arrangement and combination of parts hereinafter fully set forth and more particularly defined in the claims.

The invention is clearly illustrated in the accompanying drawings, in which:

40 Figure 1, is a perspective view of a sewing machine embodying a simple form of the present invention; Fig. 2, is a side elevation thereof, with the sewing machine head partly broken away; Fig. 3, is a plan looking at the under side of the sewing machine head and work support; Fig. 4, is an end view of the work support and its cover, and a fragment of the base, looking in the direction of the arrow 4, in Fig. 2; 45 Fig. 5, is a detail, vertical cross-section taken on the line 5—5 of Fig. 3; Fig. 6, is a face view of a fragment of a coat sleeve and lining showing the lining and sleeve sewed together by a machine embodying the present invention, and Fig. 7, is a fragmental face 50

view of said lining and sleeve after the sleeve lining has been turned back from the position seen in Fig. 6, and showing the coat sleeve lining and the seam in their finished form.

Referring to said drawings, the reference character 10, designates a "Singer" zig zag, lock stitch, sewing machine head, the mechanism of which is of well known construction and requires no detailed description so far as this specification is concerned. Reference is made to Patent No. 1,020,089, issued March 12, 1912, to C. F. Gray. The sewing machine head chosen for the purpose of illustration, is one made by the Singer Sewing Machine Co., and, as is well known to those skilled in this art, this machine sews a zig zag, lock stitch, such as is illustrated graphically in Fig. 6, the needle being shifted sidewise by suitable mechanism each time the material is fed forward by the feed dog. The work support or base plate of the ordinary "Singer" zig zag, lock stitch sewing machine head as disclosed in said patent rests directly upon the sewing machine table and is too wide to permit a sleeve to be placed around same in sewing a seam around its circumference. In the present invention we have narrowed that part of the work support which extends from its connection with the arm of the machine head, to and under the needle, and have re-arranged and re-constructed the mechanism between the drive shaft of the sewing machine head and the feed dog and shuttle carrying hook, and have provided means for supporting said extension of the base above the sewing machine table so as to permit a sleeve to be placed around said extension to enable it to sew the seam which connects the lower end of the sleeve lining with the sleeve.

The base of the sewing machine head is illustrated at 11, and comprises a stationary portion 12, which is fixedly secured to the sewing machine table, and a hinged portion 13, which is hinged to the stationary portion by means of hinges 14. Preferably, the base portion 11, is made hollow and receives any oil drippings that may come from the interior of the arm. A clamp plate 15, is provided upon the stationary base portion 12, and engages with a rib 16, upon the hinged portion 13, a thumb screw 17, extending through said clamp plate 15, and 110

being threaded in the wall of the stationary base 12, for clamping the clamp plate 15, upon the rib 16, and thereby fixedly securing together the two portions of the base.

5 The arm and hinged member 13, of the base may be secured together in any suitable manner or may be cast integral with each other as desired. Said hinged base portion 13, is formed with a work support 18, at 10 its upper end which underlies the arm of the sewing machine head and extends beyond the presser foot and needle, as is customary, but said work support 18, is made considerably narrower beyond the base portion 11, as is clearly seen in Figs. 1 and 3. It is made narrow enough to permit a sleeve of small size to be slipped over same when sewing the lower end of the sleeve lining to the sleeve itself.

15 20 Below the work support 18, is a cover 19, which incloses the operative parts of the machine below the work support 18, and said cover is detachably secured to the work support, as for instance, by providing a lug 20, 25 on one end, that enters a notch in the base 11, and engages with the inner side thereof and acts as a hinged connection between the cover 19, and base 11, whereby it may be permitted to swing down to expose the operative parts to view, such position is seen in dotted lines in Fig. 2. A latch plate 21, 30 secures the cover to the work support and said latch plate covers an opening in the upper side of the work support and is slidably held upon depressed portions 22, of the work support by springlike arms 23, secured to the underside of the latch plate and pushing against the underside of said depressed portions 22. Said latch plate 21, 35 40 has a dove tail connection 24, with the cover 19 (see Fig. 4) comprising a lug on the underside of the latch plate which is slideable into and out of a notch in the end of the cover; the sides of the lug and notch of 45 the cover are inclined, as seen in Fig. 4, to afford the dove tail connection.

Supported upon the underside of the work support are the shuttle carrying hook and feed dog actuating mechanism. These parts 50 are well known and are comprised in the "Singer" zig zag, lock stitch sewing machine illustrated herein, but we have rearranged many of the parts, have reconstructed others and have changed the location of many to enable a narrow work support to be employed so that the machine may be adapted for sewing the lower end of sleeve linings to the coat sleeves. In this reconstructed machine, the hook driving 55 bevel pinion shaft 25, the feed lifting hollow rock shaft 26, which surrounds said rock shaft 25, and the feed driving rock shaft 27, have been brought closer together than in the ordinary "Singer" zig zag, lock 60 stitch sewing machine, and their bearings 65

28, 29, 30, 31, have been located to allow for the new location of the shafts. Upon the hook driving bevel pinion shaft 25, is the usual hook driving bevel pinion 32, which meshes with the usual hook driving 70 bevel gear 33, which is fast upon the hollow hook shaft 34. Said shaft 34, is journaled in the hook shaft bushing 35, which is fixedly secured in the hollow lug 36, cast upon the lower face of the work support 18. The usual hook 37, is secured upon the shaft 34, by the hook position screw 38, which extends through the hollow shaft 34. The hook 37, is arranged to contain the bobbin and bobbin case (not shown) as is 80 customary. The lug 36, bushing 35, hollow shaft 34, and screw 38, have been shortened to bring their outer ends flush with the side of the work support, without, however, changing the location of the hook 37, which 85 has a definite location relative to the sewing machine needle as is readily understood.

The feed lifting hollow rock shaft 26, and feed driving rock shaft 27, coöperate to actuate the feed dog 39, in the usual manner, but 90 the feed dog bar 40, which connects with the feed lifting crank 41, is made shorter than usual because of the closer relation of the shafts 25, 26, 27. The rock shaft 27, with its crank arm 42, terminates back of the feed 95 bar 40, and the latter is pivotally secured to the crank arm 42, by the feed bar hinge screw 43. The shafts 26, 27, have the usual connection cranks 42¹, 43¹, secured thereon, connected to the usual feed driving connections 44, 45, that receive their reciprocatory movements from mechanism contained in the head, and the shaft 25, is driven by a chain 46, as is customary in the "Singer" zig zag, lock stitch sewing machine.

No detailed description of the "Singer" zig zag lock stitch operating mechanism is thought necessary so far as this specification is concerned, as those parts are well known to those skilled in the art to which this invention pertains and the operation of a "Singer" zig zag, lock stitch machine requires no especial explanation so far as this specification is concerned. The form of stitch is clearly shown in Fig. 6, and a machine adapted for sewing this stitch is used because this type of stitch does not ravel, and acts as a hinge in turning the lining over upon itself in bringing the sleeve lining to the inside of the sleeve.

In use the side seams of the sleeve A, and its lining B, are first made and the lining placed around the sleeve, the sleeve being right side out but the lining being inside out. The lower end of the lining is folded on 125 itself, as at b, in Fig. 6, and the zig zag seam b¹, is made along the line of the fold. To sew the lower end of the lining to the lower end of the sleeve, the sleeve is slipped around the covered work support 18, bringing the 130

folded edge of the lining in line with the sewing machine needle; the machine is then started and the seam b^1 , sewed around the sleeve. The material will travel around the 5 work support 18, without difficulty, and thus the seam b^1 , may be readily sewed around the sleeve. After this seam is made the lining is turned into the inside of the sleeve along the seam b^1 , as a hinge or pivot, and 10 the material of the sleeve is allowed to project down an inch or so, as is usual, to give a finished appearance to the inside of the sleeve. The row of stitching which shows in the finished sleeve is illustrated graphically in Fig. 7, and has the appearance of a hand sewed seam, with regular, even stitches. 15

We claim as new and desire to secure by Letters Patent:

1. A sewing machine for sewing the lower

end of sleeve linings to coat sleeves, comprising 20 a zig zag, lock stitch sewing machine head, having a narrow work support for supporting the feed dog and hook actuating mechanism, a cover hingedly secured to the under side of said work support, and a base 25 for supporting said work support above a sewing machine table, whereby a coat sleeve and its lining may be slipped around said work support and its cover to sew a seam around said lining and sleeve. 30

2. A zig zag, lock stitch sewing machine head of the type described, having a narrow, work support carried free from a table on which the head is supported and having a cover removably and hingedly secured at the 35 lower side of said work support.

EDWARD A. KAUMEYER.

DAVID M. BLOOM.
